DESIGN FOR A COMBINED SHOE SOLE AND HEEL

Curt Wolfelt, New York, N. Y.

Application September 27, 1944, Serial No. 115,473

Term of patent 7 years

(Cl. D7—5)

To all whom it may concern:

Be it known that I, Curt Wolfelt, a citizen of the United States of America, residing in New York, county of New York, and State of New York, have invented a new, original, and ornamental Design for a Combined Shoe Sole and Heel, of which the following is a specification, reference being had to the accompanying drawing, forming part thereof.

The figure on the drawing is a perspective view of a combined shoe sole and heel showing my new design.

The dominant feature of my design resides in the portions shown in solid lines.

I claim:

The ornamental design for a combined shoe sole and heel, substantially as shown and described.

CURT WOLFELT.
